SAFETY PAPER AND METHOD OF MAKING
THE SAMEBurgess W. Smith, Rochester, N. Y., assignor to
The Todd Company, Inc., Rochester, N. Y., a
corporation of New YorkNo Drawing. Application August 22, 1932, Serial
No. 629,889

4 Claims. (Cl. 91—67.95)

This invention relates to safety paper for making bank checks, drafts, bonds, or any other document in which it is desired that erasures made with chemical ink eradicator be indicated by a stain or discoloration, and to methods of making the same.

The object of my invention is to provide a more practical and efficient paper of this character, capable of being inexpensively manufactured in the desired commercial form, as well as a more practical and efficient method of making the same. More particularly, it is the object of the invention to provide a paper which will be quickly and conspicuously discolored by the action of ink eradicator, regardless of the order of application of its components, or its acidity, and method of making the same.

To these and other ends, the invention resides in certain improvements, combination of parts and method steps, all of which will be more fully described, the novel features being pointed out, in the claims at the end of this specification.

In the preparation of the class of safety papers in which the use of ink eradicator produces a stain, the active ingredient for maximum efficiency should possess certain characteristics. The material should be relatively stable to normal influences, and the stain when produced should resist removal by reagents commonly known and used for this purpose. It should react with the commonly used ink eradicator, which is composed of an alkaline hypochlorite, generally hypochlorite of soda, used in combination with a second component consisting of a solution of tartaric acid. For maximum efficiency it should react in either acid or alkaline condition of the hypochlorite of soda or other eradicator.

I have found that compounds having two benzene rings linked together by the linkage—

in which the component X may be—

45

with at least one amino radical on each ring para to that linkage, will develop a conspicuous stain with hypochlorite of soda ink eradicator in any order of application, or in either alkaline or acid condition.

Compounds of this class are represented by p,p'-diaminodiphenyl sulfide, p,p'-diaminodiphenylether, p,p'-diaminodiphenylamine, p,p'-

diaminotriphenylamine, or any other compound having a substitution for the X component that retains the aforesaid characteristic of color development with acid hypochlorite such as exhibited, for example, by p,p'-diaminodiphenyl sulfide.

I prefer the use of diaminodiphenyl sulfide inasmuch as it may be easily and cheaply prepared in a high order of purity by heating sulfur with aniline in the presence of a catalyst, two chemicals available commercially in large quantities, and readily accessible at a low price.

In the form of the base this compound is reasonably stable, but it is much more so in the form of its salts, of which the sulfate is probably the most stable. The sulfate, having a high degree of insolubility, may be incorporated in the paper in that form when the paper is being made, by the introduction in the beater, the Jordan, or by sprinkling or otherwise applying it to the web in process of formation.

It may be precipitated as the sulfate from the hydrochloride, which may be in a state of solution in the beater, or in any other suitable stage in the process of manufacturing paper, such as the incorporation of it in the sizing.

I may use such a compound in an ink prepared with any of the commercially known varnish mediums, or use a more novel medium which is a solution of cellulose nitrate in diethylene phthalate. Inks of this nature may be applied as a general surface coating, or used to form a warning word or symbol such as described in my Patent No. 1,454,837.

The quantities and proportions used for this purpose depend entirely on the desired depth of stain or discoloration, and the application of this material involves no special skill not possessed by one familiar with this art.

Paper having incorporated therein or thereon organic compounds of the class described will indicate or show the application of the usual commercial eradicator by developing a conspicuous brown color that is extremely difficult if not impossible to remove without conspicuously defacing or destroying the paper.

While certain substances and methods have been referred to herein by me, and specifically described, it is to be understood that other closely related substances containing the linkage—

are included in this invention, particularly the homologues and analogues of the compounds

named, and other methods of application of these compounds, as are well understood by those skilled in this art, may be used without departing from the spirit of this invention.

5 It is to be further understood that the term "paper containing" means that the material may be on the surface alone, incorporated in a film intimately attached thereto, or in the body of the paper. The term "safety paper" means any 10 paper or writing surface on which it is desired to indicate the application of a chemical ink eradicator by the production of a stain or discoloration.

I claim:

15 1. A safety paper containing a salt of p,p'-diaminodiphenyl sulfide.

2. A method of making safety paper comprising the step of adding the sulfate of p,p'-diaminodiphenyl sulfide during or after the formation of the web for the purpose of producing, by its reactions, a visible indication of the use of a 5 chemical ink eradicator.

3. A safety paper containing a sulfate of p,-p'diaminodiphenyl sulfide.

4. The method of making safety paper comprising the step of adding a salt of p,p'-diamino- 10 diphenyl sulfide during or after the formation of the web for the purpose of producing, by its reactions, a visible indication of the use of a chemical ink eradicator.

BURGESS W. SMITH. 15
